Term of patent 14 years

Int. Cl. D2—03

U.S. Cl. D2—259

Fig. 1

FIG. 1 is a front perspective view of ear muffs showing my design;

FIG. 2 is a front elevational view thereof, the broken line showing of a wearer being for purposes of illustration only; and

FIG. 3 is a side elevational view of the ear muffs.

The characteristic feature of my design resides in the combination on the ear muffs disclosed of the arcuate tear shaped ear portions with the head band portion all as shown on the drawing.

I claim:

The ornamental design for ear muffs, substantially as shown and described.
